(57) **CLAIM**

The ornamental design for a peanut butter stirring device, as shown and described.

DESCRIPTION

FIG. 1 is a perspective view of the peanut butter stirring device showing my new design; an exemplary handle and an exemplary bearing being shown in broken lines;

FIG. 2 is a front elevation view of FIG. 1; the rear elevation being a mirror image thereof; an exemplary jar being shown in broken lines;

FIG. 3 is a left side elevation view of FIG. 1;

FIG. 4 is a right side elevation view of FIG. 1;

FIG. 5 is a top plan view of FIG. 1; and,

FIG. 6 is a bottom plan view of FIG. 1.

The broken lines form no part of the claimed design.
